UNITED STATES PATENT OFFICE

161,809

COMBINED CHAIR AND DESK

Sumner C. Willis, White Plains, and Laurence W. Brulin, New York, N. Y., assignors to American Seating Company, Grand Rapids, Mich., a corporation of New Jersey

Application March 2, 1950, Serial No. 8,249

Term of patent 14 years

(Cl. D33—11)

To all whom it may concern:

Be it known that we, Sumner C. Willis and Laurence W. Brulin, citizens of the United States and residents, respectively, of White Plains, in the county of Westchester and State of New York, and New York, in the county of New York and State of New York, have invented a new, original, and ornamental Design for a Combined Chair and Desk, of which the following is a specification, reference being had to the accompanying drawing, forming a part thereof.

Figure 1 is a front and right-hand side perspective view of a combined chair and desk, showing our new design; and

Figure 2 is a rear and left-hand side perspective view of the same.

We claim:

The ornamental design for a combined chair and desk, substantially as shown.

SUMNER C. WILLIS.

LAURENCE W. BRULIN.
